UNITED STATES PATENT OFFICE.

CHARLES PARNELL THOMAS, OF SAN FRANCISCO, CALIFORNIA; FRANK J. RICH
ADMINISTRATOR OF SAID CHARLES PARNELL THOMAS, DECEASED.

AUTOMATIC TRAIN-CONTROL SYSTEM.

1,370,930.

Specification of Letters Patent.

Patented Mar. 8, 1921.

Application filed August 13, 1919. Serial No. 317,147.

To all whom it may concern:

Be it known that I, CHARLES PARNELL THOMAS, a citizen of the United States, residing at the city and county of San Francisco and State of California, have invented new and useful Improvements in Automatic Train-Control Systems, of which the following is a specification.

This invention relates to a safety control 10 for trains.

As the result of extended experiment, railroad experts have agreed that an automatic train control system operating in conjunction with the present block signal system 15 and designed to bring a train to a stop, under certain conditions would be highly desirable, both in preventing accidents and also in controlling the movement of trains and placing the individual trains under the 20 control of a system which would record the detailed performance of the trains in relation to other trains and in relation to a block signal system. It is apparent that to produce an apparatus for carrying out such a 25 system, this should be of universal application to the present rolling stock trackage and motive powers, irrespective of train speeds, weather conditions, wear oscillation or shock while insuring that the removal or 30 failure of any essential part of the apparatus will display a stop signal and apply the brakes. Furthermore, this apparatus should be capable of control by and operative with the ordinary block signal system to act to 35 bring a train to a stop under predetermined conditions without permitting the release of the brakes until the train has come to a full stop or the predetermined conditions eliminated. Such a system should also make provision for permitting a train to pass an automatic stop in tripping conditions under 40 certain permissible circumstances and also furnish clear signal lights upon the train for the guidance of the engineer; for providing means operating in conjunction therewith to permanently record the continuous 45 performance and the interval of illumination of the signal lights. It is the principal object of the present invention to provide 50 an apparatus and system of control which will fulfil all of the foregoing requirements in a positive and reliable manner.

In carrying out the present invention, it is contemplated to use an apparatus consisting 55 of a signal light unit, a recording device

and an automatic air-brake control mechanism, the recording device and the air-brake control mechanism being inclosed within a locked box and inaccessible to any one save the inspector in charge of the train, while the 60 signal lights are disposed in the path of the engine, all of which units are vitally connected and are adapted to be placed in operative connection with the usual block signal system to continuously supply the engineer with a signal as to the condition of the track and to provide means for automatically setting the brakes of the engine and thereafter restoring the brake valve to its original position after the train has 70 come to a stop.

The invention is illustrated by way of example in the accompanying drawings, in which:—

Fig. 1 is a view in side elevation, illustrating a locomotive and more particularly disclosing the location of the various units of the present apparatus in relation thereto. 75

Fig. 2 is an enlarged view and diagram showing the connections between the portion of the apparatus carried upon the locomotive and a block signal semaphore. 80

Fig. 3 is a view and plan illustrating the contact breakers carried by the locomotive.

Fig. 4 is a fragmentary view in side elevation, illustrating a detail of the switch mechanism, as seen on the lines 4—4 of Fig. 6. 85

Fig. 5 is a view in section elevation, showing a detail of the switch mechanism as seen on the lines 5—5 of Fig. 6. 90

Fig. 6 is an enlarged view and diagram, illustrating all of the elements of the present apparatus and more particularly disclosing the electrical connections provided 95 therefor.

In the drawings, 10 indicates a locomotive, upon which the present invention is adapted to be installed. This apparatus consists of an automatic control unit mounted within a 100 box, as indicated at 11 and which is in communication with signal lights 12 and a contact mechanism 13. The box 11 is preferably disposed beneath the seat in the cab of the engine, while the signal lights are 105 mounted in plain view of the engineer while in driving position. The contact mechanism 13 is preferably suspended from one of the trucks of the locomotive tender and is connected with the control unit 11 by a conduit 110

14. A conduit 9 connects the box with the light 12, thus establishing electrical communication between the various units of the present apparatus and also insuring thereby 5 that electric communication will be established with the block signal system.

The box 11 is preferably made of metal and fitted with a door which may be locked. This will protect the contents of the box and 10 will preclude the possibility of tampering with the record disks inclosed thereby. If the structure is locked by the inspector at the beginning of the run, it is not intended to be opened until the train has concluded 15 its run and the disks removed by an inspector. Within the box 11 is a four-point release valve 15. This valve is provided with the necessary train connections and will control the air leading from the air-lines to the 20 brakes. The valve 15 is fitted with a pivoted handle 16; the upper end of this handle carries a shackle member 17 pivoted thereto by means of a pin 18. The shackle member is fitted with a shackle rod 19 extending to a 25 link 20. The connection between the link 20 and the shackle member is a pivoted one and provides that the rod 19 may swing horizontally in relation to the link. The opposite end of the link 20 is provided with a 30 pivot pin 21 which connects the link to a cross-head member 22. This cross-head stands vertically and the pin 21 is so disposed in relation thereto as to allow vertical swinging movements of the link. By this 35 arrangement, it will be seen that a universal connection is provided between the shifting lever 16 and the cross-head 22.

The cross-head is fitted with oppositely and horizontally extending piston rods 23 40 and 24, each of these rods is provided with a piston 25 at its outer end. The rods 23 and 24 with their pistons extend into operating cylinders 26 and 27. These cylinders are in longitudinal alinement and are spaced 45 a distance from each other, as determined by a connecting bar 28 which is secured to the adjacent heads of the cylinders. The combined links of the rods 22 and 23 and the intervening portion of the cross-head is such 50 as to insure that when one of the pistons is at the extreme end of its stroke the other piston will be at the extreme opposite end of its stroke, that is, one piston will be against the end of the head to which air is admitted and the other piston will be against 55 the opposite end of the head from that through which it is admitted. The cylinders are both supplied with outer removable heads 29, to which supply pipes 30 and 31 are connected, it being understood that 60 each head is fitted with one pipe and as indicated in the drawings, the cylinder 26 will be supplied by the pipe 30 and the cylinder 37 by the pipe 31. These pipes lead to the 65 opposite sides of a two-way air-valve 32,

which is preferably disposed at a point midway the distance between the adjacent ends of the cylinders 26 and 27. The air-valve is supplied with air under pressure in an auxiliary air-supply pipe 33 leading to an auxiliary air-tank 34, which is disposed in some convenient position upon the locomotive and is adapted to furnish air independent of the operation of the main air supply lines. The valve is also provided 75 with an exhaust pipe 34', which is controlled by a release valve 35 adapted to be regulated so that the exhaust air may be controlled as it flows from the valve and this in turn determining the period of time required for 80 the pistons to make their strokes.

The valve mechanism 32 is so designed that communication may be alternately established between the supply pipes 30 and 31 and the intake pipe 33, at the same time 85 permitting communication between one of the pipes 30 or 31 and the exhaust pipe 34'. Due to this arrangement air may pass in from the pipe 33 to pipe 30, for example, while the air is passing outwardly through 90 pipe 31 to the exhaust pipe 34'. A reversal of the position of the valve member will act to reverse the direction of flow of the air through the two pipes. In order that the movable member of the valve 32 may be operated by the change in position of the cross-head 22 and will be instantly opened and closed without any intermediate movement, a peculiar control mechanism is provided. This structure comprises a valve handle 36, 95 which is keyed to the valve stem 37. This handle is provided with a coil spring 38, which is connected to one side of the cross-head 22, and will be tensioned by the movement of the cross-head from one of its 100 extreme positions to the other. The stem 37, upon which the valve is secured and to which the shifting lever 36 is also fastened is provided with a lock cam 39, which is formed with a recess 40. This recess determines the intended rotation of the valve and is adapted to be alternately engaged by lugs 105 on pawl members 42 and 43. The pawl members are mounted upon a common hinge pin 44 carried by a fixed bracket of the 110 structure. These members are also provided with a spring 45 which presses down upon both of them and acts to hold their lugs against the periphery of the cam 39. In the position shown in Fig. 6, the cam is 115 locked against rotation by its recess 40 receiving the lug of the pawl 42 while the lug of the pawl 43 is abutting against the periphery of the cam 39. In order that the pawls will be released from their engagement with the recess of the cam 39 at pre-determined points in the stroke of the pistons and to further insure that the valve member will instantly move from opened 120 to closed positions or reverse, a releasing cam 125 130

47 is provided and is mounted to freely rotate upon the valve stem 37. This cam has two faces, one of shorter radius than the other and so arranged that the shoulders 5 formed by the continuance of these faces around the periphery of the cam will form a lift to act against the pawls 42 and 43 to release them when desired. Rotation of the cam 47 is produced by a shifting lever 10 48, which is mounted to freely rotate upon the stem 37 and is fixed in relation to the cam 47. The shifting lever 48 is formed with a forked outer end adapted to receive a cross-head pin 49. The cross-head pin will, of course, move with the cross-head 22 and will act to swing the shifting lever 48 from one of the extreme positions of the cross-head to the other and will thus produce a rotary action upon the cam 47 which will 15 bring the swells of the cam into engagement with the pawls and permit the release of the cam 39 so that the tension will cause the valve member to instantly open or close as the case may be.

20 The cross-head 22 is normally locked in the position shown at Fig. 6 by means of a spring-pressed pawl 50, which is held down against the upper face of the cross-head and in an obstructing position in relation to a shoulder 51; to prevent movement of the head a spring 52 is provided to produce this motion, while an upwardly and rearwardly extending trip lever 53 is formed as a continuation thereof to provide for the 25 release of the pawl, as it swings around its pivot pin 54 carried upon the cross-connecting member 28. The trip lever is adapted to be struck by a detent 55 which is superimposed above the lever and is normally held out of contact therewith by solenoids 56 and 57. These elements are included within a closed circuit, which will influence the cores of the solenoid to draw a cross-bar 58 upwardly and to thereby support the detent 55. Sides 59 are provided at 30 opposite ends of the cross-bar to properly control the path of travel of this bar and the weighted detent 55 which extends upwardly to other guide-plates 60. It will thus be evident that when the circuit of the solenoid is broken the member 55 will be permitted to fall and in so acting will strike the upwardly projecting lever 53 to release the pawl 50 from engagement with the 35 shoulder 51 of the cross-head.

The breaking of the solenoid circuit may be produced by the accidental interruption of the flow of current or the removal of certain of the elements of the structure, thus 40 insuring that under circumstances of accident, the structure will be operated to set the brakes. This circuit may be interrupted intentionally and automatically by means of a switch-board 61 which is also mounted within the case 11 and is operated by the

movement of the cross-head. This board carries a rotating shaft 61' mounted in suitable bearings at the upper and lower ends of the boards and also carries three contact members 62, 63 and 64, respectively. The 5 contact member 62 may be brought to engage a fixed contact 65 upon one side of the shaft 61' or a fixed contact 66 upon the opposite side of the shaft, while the contact member 63 is intended to normally make 10 connections with the fixed contact 67. The contact 64 is normally in connection with the fixed contact 68 carried upon the board. This connection is maintained by a plurality of coil springs 69 mounted around the 15 shaft 61 and secured at their opposite ends to pins 70 and 71, as clearly shown in Fig. 5. One of these pins in each instance is fitted to the fixed bearing of the switch-board and the other fitted to the movable 20 contact member, so that the influence of the spring will be to normally hold the contact. The contacts may be broken by the movement of the cross-head, which as shown in Fig. 6 is provided with the pin 21 extending 25 outwardly to engage a shifting pin 72 extending upwardly into the path of travel of the pin 21 and supported upon a switch lever 73, as more clearly indicated in Fig. 4. This lever is fixed upon the upper end of 30 the switch shaft 61 and when the cross-head 22 moves toward the opposite end of its stroke, it will relieve the pin 72 and will permit the springs 69 to uncoil in a manner 35 to swing the contacts from their position, shown in Fig. 6 and to the dotted line position indicated in Fig. 4.

For the purpose of producing a permanent record of the train performance representing the various intervals of travel of 40 the train under different conditions and recorded in chronological order, a recording device 74 is provided and is mounted within the control box 11. This device consists of a dial 75 carrying tapered disks upon which 45 three concentric marks are circled 76, 77 and 78 are printed. This disk is adapted to be driven by suitable clock-work inclosed within the case 79 and to be marked by a stylus 80 carried upon a stylus arm 81. This 50 arm is normally held in a central position by means of opposing springs 82 which will dispose of stylus 80 upon the central circle 77. The arm 81 is pivoted from one end 55 upon a pin 83, while its opposite end extends between magnets 84 and 85. These 60 magnets are adapted to alternately influence the arm to swing it up or down against the action of the springs 82 and to move the stylus toward the mark 76 or the mark 78. 65 These three recording marks correspond to lamps mounted within the cabin of the locomotive, as more generally indicated in Fig. 1 by the numeral 12. The inner indicating circle 76 is intended to agree with 70

a blue light 86, while the intermediate circle 77 agrees with a green light 87 and the outer circle 78 agrees with a red light 88. These lights, of course, would bear their usual significance in railroad signaling, the green light indicating a clear track ahead, the blue light indicating that the locomotive was proceeding upon the time of another train and that the other train or 10 locomotive was possibly carrying the signal and the red light indicating danger.

All of the apparatus described in the foregoing portion of the specification has proper correlation, due to numerous electric 15 circuits which will be hereinafter described, while these circuits bear a definite relation to a block signal system as indicated in Fig. 2 of the drawings. In this figure, 89 indicates the usual block signal system, carrying 20 a semaphore 90 and provided with a set of storage batteries 91 mounted within this semaphore case. The circuit of these storage batteries is controlled by contact members 92 and 93 which are normally in contact and may be separated to break contact by the movement of a releasing member 94, which is actuated when the semaphore is moved from its raised or non-signaling to a 25 danger signaling position. The contact 30 members 92 and 93 are connected with conductors 95 and 96, respectively. The conductor 95 leads to one pole of the batteries 91, while the conductor 96 leads to a contact rail 97, as clearly shown in Fig. 2. This rail 35 is of comparatively short length and is a companion to rail 98 carrying a conductor 99, which leads to the opposite pole of the battery 91. These rails are parallel to each other and are disposed between the traffic 40 rails 100 and 101. The incomplete circuit carried to the rails 97 and 98 are continued through the locomotive by contact plates 102 and 103, which are adapted to be pivoted to fastening members 104 and there- 45 after preferably secured to the tender trucks of the locomotive. The contact member 102 is provided with a conductor 104 which leads to a storage battery 105 carried upon the locomotive. The opposite pole of this 50 battery is fitted with a conductor 106, leading to the solenoids 56 and 57. These members are connected in parallel. The opposite poles of the solenoids are in communication with conductors 107 and 108 leading 55 to a master switch 61 through which the circuit may be completed to a conductor 109 connected with the contact plates 103. When all of the conditions are fulfilled, it 60 will thus be seen that the semaphore apparatus, the semaphore rails and the solenoids 56 and 57 are all in a single circuit.

In order that the solenoids' circuit will be at all times closed and in series with the source of electric energy 105, a circuit 65 breaker 110 is provided. This structure is

clearly shown in Figs. 2 and 3, where it will be seen to include a cage suspended from the trucks of the locomotive tender, and disposed to stand midway between the semaphore rails 97 and 98, and adapted to be 70 supported above a circuit breaker rail 111 which is disposed between the semaphore rails 97 and 98. The circuit breaker comprises a pair of coils 112 and 113 having cores 114 which extend downwardly and 75 above the rail 111. These cores do not, however, touch the rail but are adapted to be close enough to be influenced by the mass of steel therein. Extending horizontally through the cores are copper bolts 115 80 which carry an armature plate 116, this plate being spaced from the side of the cores and fitted with a pair of compression springs 117 adapted to act to normally hold the armature away from the side of the 85 cores. A contact member 118 is carried by the armature and may be moved into engagement with contact members 119 and 120. These last named members are fitted with conductors 121 and 122, respectively. 90 The conductor 121 is connected with the contact plate 103, while the conductor 122 is connected with the contact plate 102, and when the circuit is completed across the contacts 119 and 120 will act to form a continuous circuit through the conductors 104, 109, the solenoids 56 and 57 and the conductors 106 and 109, normally insuring a closed circuit through the solenoid. This circuit is normally closed due to the fact 95 that the coils 112 and 113 will act to influence the armature 116 to draw it against the side of the cores 114 and thus force the member 118 into the gap between the contacts 119 and 120. It will be evident that 100 when the large body of steel 111 is present beneath the cores 114 that the magnetic flux will be shunted and will be directed toward the larger mass of metal 111 in preference to the small armature 116. This will cause the 105 effort to be diverted from the armature and will permit it to move away from the contacts 119 and 120 under the influence of the springs 117, thus breaking the circuit 110 through contacts 119 and 120 and permitting this circuit to be completed by means of the contact plates 102 and 103, which will then act to include the block signal 115 semaphore apparatus in the solenoid circuit.

It will be understood that the lead wire 109 is connected to both of the contact members 63 and 64 of the master switch 61 and will thus be placed in communication with the contacts 67 and 68 of this switch, thereafter passing through the wires 107 and 108 to the solenoids. The circuit will be completed, of course, through the wire 106, which returns to the source of supply 105.

The conductor 109 is interrupted at a 130

point in its length by means of a multiple point switch 123, this switch has a movable contact member 124 which may be used to establish contact between the points 125 and 126. From the points 125 and 126 there is provided a shunt circuit including the wires 130, 131 and 132. Wire 130 leads to one pole of the green light 88. Wire 131 leads from the other pole of the lamp 88 to the stationary contact 62 of the master switch 61 and from thence the shunt circuit is completed by the contact 62 of the master switch 61 and wire 132 connected therewith and leading to the point 126 of the switch 123.

The red signal light 87 is provided with a wire 133 which connects with the contact member 66 of the master switch 61. This wire 133 leads to one pole of the lamp 87, while the other pole is connected by a wire 134 with the return wire 106. The circuit when completed is from the source of electric supply 105, the wire 104 and the block signal wires or the circuit breaker wires 122 and 121 to the wire 109, from thence flowing to the switch 123 to a wire 132 which is connected with the movable contact member 62 of the master switch 61. The circuit at this point is normally opened and closed when the contact 62 is brought to engage the stationary contact 66, the circuit from there on being completed through the wire 133, light 87, and wire 134 to the return wire 106. The wires 133 and 106 are provided with conductors 135 and 136 which connect with the magnet 84 and will act to draw the armature of the lever 81 upwardly when this magnet is energized. The red signal light circuit also is connected with an alarm bell 137, which is connected by a wire 138 to the conductor 133 and by a wire 139 to the return conductor 134. This means an establishment of the red signal will cause the arm 81 to be drawn upwardly and an alarm signal audibly made as well as visually by the lamp.

The blue light 86 is adapted to be connected in shunt with the main wires 104 and 109 which is accomplished in the following manner: A bridging switch 140 is provided and the opposite terminals of this switch are provided with conductors 144 and 145 in which the lamp 86 is connected in series and the electromagnet in multiple therewith through the wires 146 and 147. This circuit may be closed or broken at the option of the engineer by the switch 143. As is obvious the light 86 and magnet 85 will only be energized when the switch 143 is closed. Also, the closing of the switch 143 will energize the light 86 and magnet 85 irrespective of whether the portion of the main circuit through the wires 109, 121, 122 and 104 is closed, as the bridge switch 140 eliminates this portion of the main circuit. Further,

when the bridge switch 140 is closed, the main circuit through the master switch 61 and the magnets 56 and 57 is closed irrespective of whether the circuit breaker 113 is closed to close the circuit between the conductors 121 and 122. The purpose and use of the switch 140 will later appear.

In operation of the present apparatus, it will be assumed that normally the contact members of the block signal semaphore are held in separated relation to each other to open the circuit leading to the semaphore rails 97 and 98. It will further be understood that the circuit breaking apparatus 110 is so operated that a circuit will be established through the wires 121, 122, 104, 109 to the opposite sides of the source of electric energy 105. The shunt switch 140 will be open, as well as the switch 143 and the multiple pole switch 123 will be closed. When all of these switches are in this condition and the train is ready to start its run, the record disk 75 is placed upon the dial of the indicating structure within the box 79 and due to the fact that neither of the magnets 84 or 85 are energized the stylus 80 will rest upon the center or intermediate score mark 77 of the disk. This mark corresponding to the conditions represented by the green signal light 88. The box 79 is then locked and the train is ready to make its run. As the train passes along the traffic rails 100 and 101, the master switch will be held in the position shown in Fig. 6 with contacts established between the movable conductor 62 and the fixed conductor 65, between the movable contact 63 and the fixed contact 67 and the movable contact 64 and the fixed contact 68. This arrangement will establish two complete circuits namely: the magnet or main circuit which when traced leads from the battery 105 and through the conductors 104, 122, 121 and 109 to the master switch 61 and from thence through the magnets 56 and 57 to the return wire 106 and the green light shunt circuit which flows from 126 of the switch 124 through the wire 132 to the movable contact 62 of the master switch 61 and then from the contact 65 to the wire 131, lamp 88 and wire 130 to its return point 125 of the switch 124.

The green light will always be burning except under unusual circumstances and will indicate that the road is clear and that the various elements of the apparatus are in proper functioning relation to each other.

Assuming that the train is traveling along a right of way and that it enters a block which is clear, under this condition, the contact members 92 and 93 will be in connection with each other and will establish a normally closed circuit through the conductor 95, the source of energy 91, the conductor 99, the rails 97 and 98 with the contact plate and the conductor 96. When the con-

tact plates 102 and 103 strike the contact rails 97 and 98, the circuit will be carried forwardly into the apparatus of the present invention along the conductors 104 and 109 and from thence through the movable contact members 63 and 64 of the switch 61 to the fixed contact members 67 and 68. The current will then be carried through wires 107 and 108 to the solenoids 56 and 57 and will be permitted to return through the wire 106 to the source of energy 105 and from then along the conductor 104 to the contact 102. As the block is clear this will have no influence on the solenoids 56 and 57, as they are already maintained on a closed circuit by means of the circuit breaker 110, which is normally closed and will be intermittently opened at the time it passes over the rail 111.

In the event that the blocks entered by the locomotive is not clear, the semaphore arm will be raised to the position indicated by solid lines in Fig. 2 and the contact member 92 raised to break the circuit normally passing through it to the contact 93. This action will break the circuit through the solenoids 56 and 57 as it passes over the wires previously described and when the circuit breaker 110 passes over the circuit breaker rail 11, the circuit of the solenoids 56 and 57 will be broken in two places.

The interruption of the solenoid circuits will demagnetize their coils and will permit the member 55 to fall. This member, in falling will strike the trip lever 53 and lift the pawl 50 so that the air passing through the valve 32 from the auxiliary air tanks will be permitted to act against the piston 25 and move the cross-head 22 in the direction of the arrow —a—, as indicated in Fig. 6. As this movement takes place, the connecting rod 19 will be drawn and this, in turn, will swing the air-brake control handle 16 to set the brakes. Simultaneously with this movement the shifting lever 48 will be swung and as the cross-head 22 nears the other extreme end of its stroke, this lever will have rotated the cam 47 sufficiently to raise the pawl 52 and to permit the lock disk 39 to be released. This disk will then rotate, under the influence of the spring 38 which draws the shifting lever 36 of the valve. The valve 32 will be instantly reversed and air delivered through the pipe 31 to the cylinder 27. This will cause a reversal in the direction of travel of the cross-head 22 and will restore this cross-head to its original position without any operation on the part of the engineer. When the restoring action has been completed, the pawls 42 and 43 will both stand in locked relation to the disk 39 and will hold it against movement until further action. The valve 35 has been previously regulated to permit a predetermined rate of expenditure of the air within the pipes 30 and

31, so that the time required for moving the cross-head from one extreme position to the other will be definitely known and will be sufficient to insure that the train has been brought to a dead stop before the brakes are released.

When the cross-head 22 moves in the direction of the arrow —a— from the position shown in Fig. 6, it will release pressure of the pin 21 against the switch operating pin 72. When this has been accomplished the shaft 61 will just simply rotate under the influence of the various springs 69 carried thereby. This rotation will swing the contact members 62, 63 and 64 from their engaging position with the fixed contacts 65, 67 and 68. This will break the connection with the solenoids and also the green signal light circuit. At the instant, this connection is broken, the contact member 62 will move into engagement with the fixed contact 66 and will thus establish the red signal light circuit through the conductors 132, 133, 134 and 106. When this circuit is established, the solenoid 84 will be energized and will act upon the armature carried on the end of the lever 81 to draw this armature upwardly and to move the stylus into register with the outer score mark 78 upon the disk. As the disk continues to rotate the stylus will make a recording mark upon this circle of the disk and show exactly when the train passed into a danger zone and thereafter came into a condition which eliminated the elements of danger. The bell 137 will also ring at this time, due to the completion of the red light circuit.

When the cross-head 22 has made its complete cycle of operation, that is, from the position shown in Fig. 6 to the other extreme position and return, the switch shaft will be again rotated to establish a circuit through the solenoids and the green light and at the same time discontinue the various audible and visual signal devices. This action will place all of the apparatus in its normal running condition and will de-energize the magnet 84 to cause the stylus 80 to again return to its normal position in register with the intermediate recording ring 77.

In the event that the engineer proceeds into the block which is not clear, he may close the blue light circuit across the wires 104 and 109 by means of the switch 143. This will act to illuminate the blue light through conductors 144 and 145 and at the same time will furnish energy for the magnet 85, which will draw the lever 81 downwardly and move the stylus accordingly into the path of travel defined by the circle 76. It is also possible to discontinue the signaling action of the blue light by operation of the switch 143 when there is a train ahead or a locomotive ahead which will carry the sig-

nals. Also when proceeding into block which is not clear and there is a train or locomotive ahead carrying the signals, the engineer will close the switch 140, the circuit breaker 113 may then be actuated without applying the brakes for the reason that the current does not need to flow through the wires 122 and 121 to the conductor 109 but may flow directly from 104 to 109 and from thence through the magnets 56 and 57 to the common return 106.

It will thus be evident that by providing the apparatus here disclosed, it will be impossible for the engine to proceed when any part of the apparatus is disconnected or rendered otherwise inoperative, due to the fact that the circuits will be broken and the brakes set, under every condition, thus insuring complete safety, and at the same time providing audible and visual signals for the guidance and warning of the engineer.

While I have shown the preferred form of my invention, as now known to me, it will be understood that various changes in the combination, construction and arrangement of parts may be made by those skilled in the art, without departing from the spirit of the invention, as claimed.

Having thus described my invention, what I claim and desire to secure by Letters Patent is:

1. An automatic brake control system comprising an air-valve, mechanical operating means for opening and closing said valve, means normally locking said operating means with the air-valve in its closed position, an electrically controlled trip mechanism for said lock, a normally closed circuit, including said trip mechanism and means whereby the interruption of said circuit will act to release the lock and cause the brakes to be set.

2. An automatic brake control system comprising an air-valve, mechanical operating means for opening and closing said valve, means normally locking said operating means with the air-valve in its closed position, an electrically controlled trip mechanism for said lock, a normally closed circuit including said trip mechanism and means whereby the interruption of said circuit will act to release the lock and cause the brakes to be set, and automatically operating means adapted to function after a predetermined period of time to restore the brakes to their inoperative position and relock the operating mechanism of the brake valve.

3. An automatic brake control system comprising an air-valve, mechanical operating means for opening and closing said valve, means normally locking said operating means with the air valve in its closed position, an electrically controlled trip mechanism for said lock, a normally closed

circuit, including said trip mechanism and means whereby the interruption of said circuit will act to release the lock and cause the brakes to be set, and automatically operating means adapted to function after a predetermined period of time to restore the brakes to their inoperative position and relock the operating mechanism of the brake valve and a continuously operating recording device adapted to permanently record the interval of time which elapses with the brake valve closed and opened and thereby producing a continuous record of the train performance throughout its run.

4. An automatic brake control system comprising an air valve, mechanical operating means for opening and closing said valve, means normally locking said operating means with the air valve in its closed position, an electrically controlled trip mechanism for said lock, a normally closed circuit including said trip mechanism, and means whereby the interruption of said circuit will act to release the lock and cause the brakes to be set and automatically operating means adapted to function after a predetermined period of time to restore the brakes to their inoperative position and relock the operating mechanism of the brake valve and a continuously operating recording device adapted to permanently record the interval of time which elapses with the brake valve closed and opened and thereby producing a continuous record of the train performance throughout its run and visible signal means acting to indicate the opened and closed conditions of said electric circuit of the lock releasing means.

5. An automatic brake control system comprising an air valve, mechanical operating means for opening and closing said valve, means normally locking said operating means with the air valve in its closed position, an electrically controlled trip mechanism for said lock, a normally closed circuit including said trip mechanism and means whereby the interruption of said circuit will act to release the lock and cause the brakes to be set and automatically operating means adapted to function after a predetermined period of time to restore the brakes to their inoperative position and relock the operating mechanism of the brake valve and a continuously operating recording device adapted to permanently record the interval of time which elapses with the brake valve closed and opened and thereby producing a continuous record of the train performance throughout its run and visible signal means acting to indicate the opened and closed conditions of said electric circuit of the lock releasing means adapted to permanently record the interval of time which elapses with the brake valve closed and opened and thereby producing a continuous record of the train performance throughout its run and visible signal means acting to indicate the opened and closed conditions of said electric circuit of the lock releasing means and means for maintaining said circuit closed under certain predetermined conditions.

6. An automatic brake control system

comprising an air valve, mechanical operating means for opening and closing said valve, means normally locking said operating means with the air valve in its closed position, an electrically controlled trip mechanism for said lock, a normally closed circuit including said trip mechanism and means whereby the interruption of said circuit will act to release the lock and cause the brakes 10 to be set and automatically operating means adapted to function after a predetermined period of time to restore the brakes to their inoperative position and relock the operating mechanism of the brake valve and a 15 continuously operating recording device adapted to permanently record the interval of time which elapses with the brake valve closed and opened and thereby producing a continuous record of the train performance 20 throughout its run and visible signal means acting to indicate the opened and closed conditions of said electric circuit of the lock releasing means and means for maintaining said circuit closed under certain predetermined conditions and means for recording 25 the length of time which elapsed during said conditions.

7. A train controlling system comprising in combination an air-brake setting means, 30 a pneumatic actuator for said setting means, an electrically controlled retainer for said actuator, a closed circuit for holding said retainer, a magnetic circuit breaker interposed in said circuit having an armature 35 adapted to open or close the retainer circuit and to normally keep said retainer circuit closed, a separate circuit for energizing said magnetic circuit breaker, a rail over which the circuit breaker is disposed to pass where- 40 by the armature is released due to the rail being a better path for the magnetic force of the circuit breaker, and the retainer circuit thereby opened.

8. A train controlling system comprising 45 in combination an air brake setting means, a pneumatic actuator for said setting means, an electrically controlled retainer for said actuator, a closed circuit for holding said retainer, a pair of magnets interposed in 50 said closed circuit, an armature carried by said magnets adapted to open and close the retainer circuit and to normally hold said retainer circuit closed, and a rail over which the circuit breaker is disposed to pass where- 55 by the armature is released and the retainer circuit opened.

9. A train stop device comprising an air-brake setting means, a pneumatic actuator for said setting means, an electrically controlled retainer for said actuator, electro- 60 magnetic means associated with the track adapted for releasing said retainer at predetermined points and a recorder for said retainer.

65 10. In a train control system an air-brake

valve, pneumatic means for actuating said valve, said means comprising a pair of opposed cylinders, means normally locking said cylinders to hold the valve in its operative position, electrically controlled and automatically acting, release means for said lock and automatically operating means for reversing the direction of action of the pneumatic cylinders whereby the valve mechanism will be automatically restored to 75 its original position.

11. In a train control system, an air-brake valve, pneumatic means for actuating said valve, said means comprising a pair of opposed cylinders, means normally locking 80 said cylinders to hold the valve in its inoperative position, electrically controlled and automatically acting release means for said lock and automatically operating means for reversing the direction of action of the 85 pneumatic cylinders, whereby the valve mechanism will be automatically restored to its original inoperative position, and means for determining the time which will elapse between the operation of the valve cylinders 90 to render such valve operative and to restore to its closed position.

12. A train controlling system comprising in combination an air brake setting means, 95 a pneumatic actuator for said setting means, an electrically controlled retainer for said actuator, a closed circuit for holding said retainer, a pair of spaced magnets interposed in said closed circuit, an armature carried between said magnets adapted to close or 100 open the retainer circuit and to normally hold said circuit closed under the influence of the magnets, spring means by which the armature will be released from the magnets, and the retainer circuit opened when the 105 magnetic action of said magnets has decreased to a predetermined degree and a rail over which the magnets are disposed to pass whereby the magnetic action of the magnets upon the armature is decreased and under 110 the tension of the spring means the armature released and the retainer circuit opened.

13. In a train control system an air-brake valve, pneumatic means for actuating said valve, said means comprising a pair of opposed cylinders, a piston in each cylinder and a connecting rod therebetween, a cross-head carried by the connecting rod, connecting means between the crosshead and valve, locking means to hold the crosshead in position for closing the valve, electrically controlled releasing means for said locking means and automatic operating means whereby the crosshead, after its locking means has been released, will move to open 115 the valve and after a predetermined interval return to its original position.

14. In a train control system an air-brake valve, pneumatic means for actuating said valve, said means comprising a pair of op- 120 125 130

posed cylinders, a piston in each cylinder and a connecting rod therebetween, a cross-head carried by the connecting rod at a point intermediate the pistons, connecting means between the cross-head and valve, locking means to hold the crosshead in position for closing the valve when adjacent one of the cylinders, electrically controlled releasing means for said locking means, automatic operating means whereby the cross-head is given one complete reciprocation for opening the valve and returning the cross-head to its original position for closing the valve.

15 15. In a train control system an air-brake valve, pneumatic means for actuating said valve, said means comprising a pair of opposed cylinders, a piston in each cylinder and a connecting rod therebetween, a cross-head carried by the connecting rod, connecting means between the crosshead and valve, locking means to hold the crosshead when adjacent one of the cylinders and releasing means for said locking means, a pipe between the outer ends of the cylinders, a two-way valve in said pipe connected to a source of compressed air and connecting means between said two-way valve and crosshead whereby upon the releasing of the crosshead 25 the pistons will move to give the crosshead a complete reciprocation for opening the air-brake valve and returning the crosshead to its original locked position respectively.

30 16. In a train control system an air-brake valve, pneumatic means for actuating said valve, said means comprising a pair of op-

posed cylinders, means normally locking said cylinders to hold the valve in its operative position, electrically controlled and automatically acting release means for said lock and automatically operating means for reversing the direction of action of the pneumatic cylinders whereby the valve mechanism will be automatically restored to its original position and means for simultaneously restoring the locking of the cylinders when the valve mechanism has been restored to its original position.

17. In a train control system an air-brake valve, pneumatic means for actuating said valve, said means comprising a pair of opposed cylinders, means normally locking said cylinders to hold the valve in its operative position, electrically controlled and automatically acting release means for said lock and automatically operating means for reversing the direction of action of the pneumatic cylinders whereby the valve mechanism will be automatically restored to its original position, and electrical recording means for determining the time during which the air-brake valve is opened, the circuit therefor being closed and opened by the action of the pneumatic cylinders.

In testimony whereof I have hereunto set my hand in the presence of two subscribing witnesses.

CHARLES PARNELL THOMAS.
